SAFETY CONTROL MEANS WITH FLASH
TUBE FOR OVEN BURNERS

William D. Antrim, Cleveland, Ohio, assignor, by
means assignments, to Amalgated Gas Equipment,
Inc., Cleveland, Ohio, a corporation of
Delaware

Application August 18, 1945, Serial No. 611,356

2 Claims. (CL 158—117.1)

1

This invention relates to means for automatically igniting the oven burner of a gas range from a constantly burning pilot such as the pilot heretofore employed for ignition of the top burners of the range. Briefly, the invention contemplates the employment of a safety pilot immediately serving the oven burner, and a flash tube and pilot therefor effective for ignition of the safety pilot from the top burner pilot.

The objects of this invention are to provide a control circuit for such flash pilot, which circuit may employ an improved flash tube and pilot, as will appear hereinafter.

Further objects and advantages will be apparent from the following description taken in connection with the accompanying drawings in which:

Fig. 1 is a diagrammatic view illustrative of essential parts of a range embodying the invention;

Figs. 2 and 3 are enlarged details in elevation and typical section, respectively, of the flash tube and flash pilot burner or charging means appearing in Fig. 1; and

Fig. 4 is an enlarged typical section of an embodiment of the valve employed.

With reference now to the drawings, and first to Fig. 1 thereof, 1 is the main burner located within the range oven as indicated by the broken line 2, the burner being located and adapted for either baking or broiling, or both, as the case may be.

The main burner gas supply is had from the manifold 3 by way of the manual valve means 4, line 5, which includes thermostatic valve means 4b, safety valve 6 and line 7.

The valve means 4 embodies a manual on and off control as by manipulation of the handle 4a. The valve means 4b embodies a thermostatic throttling control responsive to the oven temperature had in the usual manner by a thermally responsive element 8 located within the oven and a transmission line 8a leading therefrom to the valve means. The arrangement is such, as will be appreciated by one familiar with the art, that the manual valve means having the handle 4a is ahead of the thermostatic valve means controlled by the thermal element 8 so that the operator may turn the handle 4a to full open position and the thermostatic throttling effect of the valve 4b will nevertheless follow, responsive to oven temperature.

The valve means 4 also controls the pilot line 9, the line 9 having its gas supply from the line 5, but ahead of the thermostatic valve means 4b

so that the line 9 is independent of oven temperature.

The pilot line 9 leads to a safety pilot burner 10 by way of a mixing device 10a where it is desired to employ primary air, the pilot 10 being located to provide ignition to the main burner 1.

Safety valve means is provided for control of the main burner gas supply line, responsive to the safety pilot burner 10. Details of such safety valve means are not material to this invention, but as here shown it includes a valve body 6 having a main gas inlet 5a and outlet 1a, a valve head 6a for control of the outlet 1a and shown in closed position relative thereto in Fig. 4, an element 11 in thermal responsive relation to the pilot flame 10 and suitable mechanism for control of the valve head 6a by the thermally responsive element 11. In the drawing such mechanism is of snap-acting characteristic including a link 20 carrying the valve 6a, a lever 21, having connection with the thermally responsive element 11, and a tension spring 22 effective between the link 20 and lever 21. The link 20 is seated in a bridge 23 within the valve body and the lever 21 is mounted in a sealing diaphragm 24.

The arrangement is such that the safety valve and associated parts will be in closed position as illustrated Fig. 4 to cut off gas supply to the main burner in the absence of operation of the safety pilot 10, but when the thermally responsive element 11 is heated by operation of the safety pilot 10 as indicated in Fig. 1, the safety valve will open, moving its head 6a to the left, Fig. 4, to permit gas flow to the main burner as indicated by the large arrows Fig. 4; such safety valve operation, both "on" and "off," being automatically responsive to operation of the safety pilot 10.

40 The range is provided with a constantly burning pilot 12 here shown as fed directly from the manifold 3, and which may be the usual provision for ignition of the range top burners, as through flash tubes thereto, but not here illustrated.

45 What has thus far been described is generally old and well known in the art; and this invention provides flash tube means for igniting the safety pilot burner 10 from the constant pilot burner 12, automatically upon opening of the oven burner control valve means 4.

For such purpose an open ended flash tube 13 having a cooperative flash gas supply tube may be provided as here shown. As indicated in detail in Figs. 2 and 3, the flash tube 13 is of

porous open construction as of woven wire and is flexible for ease of installation; and the flash pilot burner or charging means 14 comprises a tube extending within the flash tube 13 and a substantial distance therewith and provided therewithin with a number of small outlet ports 14a at intervals or spaced locations therewith. It will be appreciated that the flash tube and pilot here described may be, if preferred, of more conventional construction comprising the more usual rigid flash tube and single charging port or flash burner therefor.

The flash pilot burner 14 is served by a line 15 which may include the adjusting valve 16 and which is controlled automatically from the pilot 10, but subject to the pilot line 9 and consequently to the manual valve 4 also, as follows: A connection 17 is provided leading from the pilot line 9 to the body of the automatic valve 6, by way of the inlet 11a therein, the body having an outlet 15a from which the line 15 has connection. A diaphragm 18 is so arranged in the valve body that it controls flow between the openings 15a and 11a, yet maintains both these openings at all times without communication with either of the openings 5a and 1a in the main burner gas line. The diaphragm 18 is under the control of a head 19 on the main valve proper 6a, the arrangement being such that when the valve 6 opens to the main burner line 7, it closes to the flash pilot line 15 and vice versa, direction of flash pilot gas flow being indicated by small arrows in Fig. 4.

The valve means described, and herein illustrated in Figs. 1 and 4, and which is responsive to the safety pilot 10 through the action of the thermally responsive element 11, is thus of dual nature with respect to the main burner gas supply. It is a safety valve which automatically permits gas flow to the main burner, only during safety pilot operation. As to the flash tube, however, by virtue of the diaphragm 18 and head 19, it admits energizing gas to the flash tube before admitting gas to the main burner and automatically cuts off flash tube gas during operation of the main burner.

The operation will be as follows, commencing with the manual oven burner control valve means in "off" position and only the constant pilot 12 in operation:

When the operator desires operation of the burner 1, the manual valve 4a is simply turned to full "on" position, the desired thermostatic oven temperature setting having been made at the thermostatic valve 4b.

Opening of the manual valve means admits gas to the lines 5 and 9. The thermostatic element 11 being cold, the valve 6 prevents flow to the main burner supply line 7, but gas is admitted from the line 9 by way of the connection 17 past the valve 6, through the line 15 to the ports 14a of the flash pilot burner 14, thus releasing a small energizing volume of gas within the flash tube 13 with distribution therewith. This gas mingles with the air within the flash tube to form a combustible mixture which is ignited by the constant pilot 12 and in turn ignites the safety pilot 10 which latter has been receiving gas from the line 9 since opening of the manual valve so that it has been purged of air.

Ignition of the safety pilot 10 heats the thermal element 11 which in turn shifts the valve 6 to cut off gas supply to the flash pilot burner and

admit gas to the main burner 1 which is immediately ignited from the safety pilot.

On safety pilot outage for any cause, cooling of the thermal element 11 returns the valve 6 to safety position, cutting off gas to the main burner and re-admitting gas to the flash pilot for automatic re-ignition of the safety pilot from the constant pilot.

When the oven is brought up to predetermined temperature by the main burner, the thermostatic valve means 4b begins to throttle down the main burner responsive to the thermal element 8. This, however, has no effect upon the gas pressure in the line 8 so that the safety pilot 10 continues in operation without impairment of its effect upon the thermal element 11; nor, should recycling take place following outage of the safety pilot, will there be any throttling effect upon the flash pilot burner. These are important advantages particularly as to the flash, which is necessarily somewhat critical in many commercial installations.

I claim:

1. In a gas range having a top pilot burner, an oven with a main burner therein, a safety pilot arranged to serve said main burner, gas supply means for said oven burner including a safety valve means controlled by said safety pilot and manual valve means, and gas supply means for said safety pilot subject to said manual valve means: means providing ignition for said safety pilot from said top pilot burner, and including flash pilot burner means, flash tube means arranged to receive a gas charge from said flash pilot burner means, and have ignition of said charge from said top pilot burner, and means providing gas supply for said flash pilot burner means from said safety pilot supply means, and including valve means responsive to said safety pilot, to cut off said flash pilot burner means upon safety pilot ignition, and to pass gas to said flash pilot burner means upon safety pilot outage.

2. In a gas range having a top pilot burner, an oven with a main burner therein, a safety pilot arranged to serve said main burner, gas supply means for said oven burner including a safety valve means controlled by said safety pilot and manual valve means, and gas supply means for said safety pilot subject to said manual valve means: means providing ignition for said safety pilot from said top pilot burner, and including flash pilot burner means, flash tube means arranged to receive a gas charge from said flash pilot burner means, and have ignition of said charge from said top pilot burner, and means providing gas supply for said flash pilot burner means, and including valve means responsive to said safety pilot, to cut off said flash pilot burner means upon safety pilot ignition, and to pass gas to said flash pilot burner means upon safety pilot outage.

Certificate of Correction

Patent No. 2,520,298

August 29, 1950

WILLIAM D. ANTRIM

It is hereby certified that error appears in the printed specification of the above numbered patent requiring correction as follows:

Column 2, line 53, after the word "tube" insert *14*; column 4, lines 27 and 47, after "oven" insert *main*;

and that the said Letters Patent should be read as corrected above, so that the same may conform to the record of the case in the Patent Office.

Signed and sealed this 28th day of November, A. D. 1950.
